US00D832223S

(12) **United States Design Patent** (10) **Patent No.:** **US D832,223 S**
(45) **Date of Patent:** **** Oct. 30, 2018**

(54) **ACTIVE WALL PLATE**

(71) Applicant: **Darren C Knight**, Pleasant Grove, UT (US)

(72) Inventor: **Darren C Knight**, Pleasant Grove, UT (US)

(73) Assignee: **SnapRays, LLC**, Vineyard, UT (US)

(**) Term: **15 Years**

(21) Appl. No.: **29/594,002**

(22) Filed: **Feb. 14, 2017**

Related U.S. Application Data

(63) Continuation-in-part of application No. 29/522,404, filed on Mar. 30, 2015, now Pat. No. Des. 781,241, which is a continuation-in-part of application No. 14/549,143, filed on Nov. 20, 2014, now Pat. No. 9,362,728, said application No. 29/594,002 is a continuation-in-part of application No. 29/522,406, filed on Mar. 30, 2015, now Pat. No. Des. 810,697, which is a continuation-in-part of application No. 14/549,143, filed on Nov. 20, 2014, now Pat. No. 9,362,728, said application No. 29/594,002 is a continuation-in-part of application No. 14/678,746, filed on Apr. 3, 2015, now Pat. No. 9,768,562, which is a continuation of application No. 14/006,637, filed

(57) **CLAIM**

The ornamental design for an active wall plate, as shown and described.

DESCRIPTION

FIG. 1 is a perspective view of an active wall plate in accordance with my new design;

FIG. 2 is a front view thereof;

FIG. 3 is a bottom view thereof;

FIG. 4 is a left side view thereof;

FIG. 5 is a right side view thereof;

FIG. 6 is a top view thereof;

FIG. 7 is a perspective view of a second embodiment thereof; and,

FIG. 8 is a perspective view of a third embodiment thereof. The broken lines represent portions of the active wall plate and form no part of the claimed design.

1 Claim, 4 Drawing Sheets

Related U.S. Application Data

on Oct. 29, 2013, now Pat. No. 9,035,181, which is a continuation-in-part of application No. 13/461,915, filed on May 2, 2012, now Pat. No. 8,912,442, said application No. 29/594,002 is a continuation-in-part of application No. 29/551,208, filed on Jan. 11, 2016, now Pat. No. Des. 809,899, and a continuation-in-part of application No. 15/406,404, filed on Jan. 13, 2017, now Pat. No. 9,742,111, which is a continuation of application No. 15/145,749, filed on May 3, 2016, now Pat. No. 9,787,025, which is a continuation-in-part of application No. 14/549,143, filed on Nov. 20, 2014, now Pat. No. 9,362,728, which is a continuation-in-part of application No. 14/066,621, filed on Oct. 29, 2013, now Pat. No. 9,035,180, which is a continuation-in-part of application No. 13/461,915, filed on May 2, 2012, now Pat. No. 8,912,442, said application No. 29/594,002 is a continuation-in-part of application No. 15/428,099, filed on Feb. 8, 2017, now Pat. No. 9,832,841, which is a continuation-in-part of application No. 15/409,508, filed on Jan. 18, 2017, now Pat. No. 9,807,829.
